UNITED STATES PATENT OFFICE.

WALLACE CLEMENT SABINE, OF BOSTON, MASSACHUSETTS, AND RAFAEL GUASTAVINO, OF BROOKLYN, NEW YORK.

WALL AND CEILING OF AUDITORIUMS AND THE LIKE.

1,119,543.

Specification of Letters Patent.

Patented Dec. 1, 1914.

Application filed February 17, 1913. Serial No. 748,943.

To all whom it may concern:

Be it known that we, WALLACE CLEMENT SABINE, a citizen of the United States, residing in Boston, in the county of Suffolk and State of Massachusetts, and RAFAEL GUASTAVINO, a citizen of the United States, residing in Brooklyn, in the county of Queens and State of New York, have invented a new and useful Improvement in **10** Walls and Ceilings of Auditoriums and the like.

The object of our invention is to provide walls and ceilings in auditoriums and the like which shall correct certain types of **15** acoustical difficulties by the prevention, when properly used, of excessive reverberation and echo, and injurious focusing of sound.

This invention is the result of a request **20** from architects for structural walls and ceilings, which shall be at the same time finished in appearance and acoustically corrective.

In 1900, Wallace Clement Sabine, one of the applicants herein, published in *The American Architect* the result of personal investigations showing that certain types of **25** acoustical difficulties in auditoriums could be corrected by the use of fabrics, such as felt, uncovered or covered with denim, burlap, or the like. From that time to the present many of the acoustical difficulties in auditoriums have been corrected by this method. All structural walls and ceilings heretofore in use, such as brick, tile, wood **30** sheathing, plaster on wood or wire lath, and plaster applied directly to a solid support, are practically impervious to sound waves, and the diminution of incident sound is almost wholly due to the flexibility of such **35** structures, and such flexibility is so slight that for the purpose of correcting acoustical difficulties they are practically non-absorbent. All such previously known structural walls and ceilings reflect at least ninety per **40** centum of the incident sound, and in the great majority of cases more than ninety-five per centum, the loss of the remaining sound being due almost wholly to the yielding of those structures and to actual transmission. Walls to be effective in the correction of acoustical difficulties in auditoriums must be more highly absorbent especially for sounds having a pitch in the three **45** octaves above middle C. Although the fundamental pitch of the male speaking voice is

below middle C, the characteristic sounds which distinguish articulate speech lie mainly within this range.

Accordingly, the invention primarily consists in a porous artificial masonry material **50** capable of absorbing sound waves to a very high degree, and hence being specially adapted for the interior exposed face of the walls and ceilings of auditoriums and the like. **55**

Also, the invention contemplates a novel wall or ceiling structure embodying the improved material as the inner exposed layer thereof.

Further objects and advantages of the invention, in its aforesaid several aspects, will more readily appear as the description thereof proceeds, and in the accompanying illustrations.

Figure 1 is a diagram plotting the power **75** for absorbing sounds by the structure which is the result of this invention, in contrast with the sound-absorbing power of typical standard masonry structures, simple and compound. Figs. 2 and 3 are sectional views **80** of walls constructed in accordance with our invention. Fig. 4 shows a section of a wall arch constructed in accordance with our invention.

First referring to these illustrations, it **85** will be seen that in Fig. 1 the pitch is plotted horizontally as abscissæ, and the absorbing power vertically as ordinates. The tests here plotted cover a range in pitch from the second octave below to the third octave **90** above middle C. Curve 1 shows the absorbing power of a solid eighteen inch wall of finished brick. Curve 2 shows the absorbing power of the best tile heretofore in use. Such tile is a little more yielding than brick, **95** but like brick, is practically non-absorbent through porosity. Curve 3 shows the absorbing power of a plaster on lath wall, in which the resonance for the lower notes is apparent. Curve 4 shows the superior **100** acoustic effect actually obtained by using the construction described in this invention.

In Fig. 2 we have shown a structural wall **1**, constructed of masonry materials, to the interior exposed surface of which is secured by means of suitable binding material, such as cement, our porous sound-absorbing material **2**.

In Fig. 3 we have shown a structural wall **1**, to which is secured a layer of hollow **110**

blocks 3 by means of cement or other suitable binding material. To the interior surface of the hollow blocks is secured, by means of cement or other suitable binding material, our porous sound-absorbing material 2, which forms the interior exposed surface of the wall.

In Fig. 4 we have shown a structural vaulted ceiling 1, to which is secured, by a suitable binding material such as cement, our porous sound-absorbing material 2.

From the foregoing it will be seen that in the adaptation of our improved porous material to a wall or ceiling structure, the inner layer, directly exposed to the sound, is of masonry highly and peculiarly porous, in such a manner as to make it absorbent of sound, and the outer layer of which is designed for heavy pressure and structural support.

We provide one inner layer of masonry material structurally rigid in its own interior formation, and structurally a part of the wall. It may have a finished and decorative surface, and must be suitable for interior exposure, suitability for such direct interior exposure being necessary to the present invention. The outer layer may be either solid masonry or hollow for heat and moisture insulation. Its primary purpose is that of supporting the superstructure.

It is not sufficient for the purposes of this invention that the peculiar porosity of the inner layer above referred to consist merely of inclosed air spaces. Such structure is in reality cellular and without value for the purpose of this invention. The air spaces may be connecting and must constitute channels traversing the rigid structure of the porous layer, and reaching to and penetrating the interior surface. It is desirable that these channels be irregular in form, expanding and contracting in cross-section, so that their action will be like the muffling action of a muffler on an engine exhaust. Also, it is essential that the pores intercommunicate and openly penetrate the exposed face or faces of the body and shall be of such proportional and variant dimensions that said body shall possess the property of absorbing in excess of ten per centum of sounds lying in pitch between middle C and the third octave above middle C. Hence, the body of material, generally stated, is sponge-like in structure.

Thus, by porosity we do not mean the cellular structure that exists in the commercial porous block used for insulating for heat and sound. It is essential to this invention that the sound penetrate the material. Any structure which is useful in insulation must be impervious to air, and therefore unsuitable to this invention. The porous block used for sound and heat insulation, is, in theory and in fact, cellular, and

not porous, in the sense in which the word is here used.

The new material herein described may be made in different ways, but for illustrative purposes one practical method for making such material is given in the following description: Clay, flux, such as feldspar, and a vegetable bearing earth, in a slightly moist condition, are pulverized and thoroughly mixed. We have found that the proportionate size or dimensions of the pores and their consequent power to absorb sounds differing in pitch may be varied and determined according to the degree of pulverization. In this powdered and slightly moist condition the material is then screened with a screen about sixteen meshes to an inch. The powdered material is then placed in molds of suitable form and subjected to sufficient pressure to cause the particles to cohere. The blanks are then dried, after which they are placed in a suitable kiln, the temperature of which is slowly raised until the vegetable matter in the blanks is consumed, after which the temperature is raised to about 2100 degrees Fahrenheit, when the kiln is allowed to cool very slowly and the finished material or tile are removed.

In order to prevent as far as possible the closing of the pores on the exposed surface of the tile, we prefer to coat this surface of the blank with finely pulverized vegetable bearing earth. This we accomplish by sprinkling the finely pulverized vegetable bearing earth upon the bottom of the mold which forms the interior exposed face of the tile when it is incorporated into the wall of a structure or upon the upper face of the material as it lies in the mold.

We have found in our experience that the blanks cannot be satisfactorily formed in a press from which the material is extruded, as the rubbing of the materials against the walls of the dies tends to close the surface pores, which renders the finished material entirely unsuitable for our purposes.

We have found that the best ratio in which the three components should be used varies somewhat with the kind of clays and earth used. With our particular materials the following ratios give very satisfactory results. Clay 25%, vegetable bearing earth 65% and feldspar 10%.

The advantages of a wall constructed in accordance with our invention are that the desired absorption of sound and the correction of acoustical difficulties is obtained by its use, while at the same time it is structural in its nature, and forms a permanent fireproof wall or ceiling, which has to the eye the appearance of solid masonry or stone, and which may be readily cleaned.

We claim:

1. A sound absorbing wall or ceiling, in-

cluding a ceramic material whose body has an exposed finished face and is provided throughout with intercommunicating pores which openly penetrate said exposed finished face.

2. A sound absorbing wall or ceiling, including a ceramic material whose body has an exposed finished face and is provided throughout with irregular intercommunicating pores of variant dimensions which openly penetrate said exposed finished face, the said material possessing the property of absorbing in excess of ten percentum of sounds lying in pitch between middle C and 15 the third octave above middle C.

3. A wall or ceiling for auditoriums and the like, having in combination, a supporting masonry structure, and attached thereto an exposed inner layer of finished masonry 20 sponge-like in structure, the latter having pores which have rigid walls and are intercommunicating throughout the mass and openly penetrate the exposed finished surface, the said pores being of such propor-

tional and variant dimensions that said inner masonry material possesses the property of absorbing in excess of ten percentum of sounds lying in pitch between middle C and the third octave above middle C.

4. A sound absorbing ceramic material 30 having a finished surface which when in place forms the finished exposed wall or ceiling surface, such material being sponge-like in structure and provided with irregular pores which intercommunicate and 35 openly penetrate the exposed finished face or faces of such material and permit the transmission of sound into the interior of such material and provide means for the absorption thereof.

Signed at New York in the county of New York and State of New York this 7th day of February, A. D. 1913.
